DRILL PIPE RACKING CHUTE

James N. Gregory, La Habra, Calif., assignor to
 Shell Development Company, San Francisco,
 Calif., a corporation of Delaware

Application March 23, 1948, Serial No. 16,482

2 Claims. (Cl. 214—2.5)

1

This invention relates to well equipment and pertains more particularly to a method and apparatus for facilitating the racking of sections or stands of drill pipe.

During the drilling of oil wells by the rotary method, it is necessary to withdraw, at relatively frequent intervals, the drill pipe from the borehole for various reasons, e. g. to change drill bits. When removing the drill string or pipe from the borehole, the drill string is hoisted by the draw-works from the borehole to a predetermined height within the derrick. The hoisting is then stopped, slips are inserted into the opening in the rotary table around the drill pipe by the drilling crew, and the pipe or pipe stand above the slips is uncoupled from the drill string. While still depending from the elevators and traveling block, this uncoupled section or stand of drill pipe is swung by members of the drilling crew to one side of the derrick, where it is lowered until the lower end of the pipe stand rests on the operating platform or derrick floor. The upper end of the pipe section is then secured to the upper part of the derrick, or to the finger board, the section then being in its racked position, i. e. to one side of the path of the traveling blocks and elevators, thus giving the necessary clearance for the removal of the next section or stand of drill pipe. Except for the hoisting of the drill pipe, the racking operation is generally a manual operation requiring the services of two or more members of the drilling crew, and the stands of pipe are racked normally on the operating floor within the derrick so as to be available for running in the well again at a later time.

One of the primary disadvantages of racking pipe on the operating floor of a well derrick in the conventional manner is that the derrick sub-structure, supporting the operating floor, must be constructed with adequate strength to support the weight of the entire drill string when racked, said drill string usually consisting of several thousand feet of pipe. This method requires manual effort to force the lower end of a stand of pipe through a horizontal distance of several feet from its freely hanging position over the well bore to its racked position at one side of the derrick. Considerable skill is required to swing the stand pipe through its proper arc to permit correct placement of the pipe when racked, and physical hazard is involved when picking up or lowering a stand into its racked position, since inaccurate placement, slippery footing, or faulty elevators may cause the stand of pipe to be dropped causing injury. There is

also a hazard of collision between the traveling blocks and the crown blocks since the clearance between these blocks is usually very limited when a stand of drill pipe has been raised to its racking height.

5 The primary object of the present invention is to provide an apparatus for racking drill pipe in a predetermined position at a level below or independent of the derrick floor, and preferably on 10 the ground, thereby avoiding excessive loads on said floor and providing more space in the derrick for racking pipe.

It is also an object of the present invention to provide a pipe racking apparatus adapted to be 15 mounted adjacent an opening in the floor of a derrick for automatically lowering and positioning stands of pipe within said floor opening.

A further object of the present invention is to provide a pipe racking apparatus for guiding and 20 handling the lower end of a pipe stand being racked whereby the occupational hazards to the drilling crew are eliminated or greatly minimized.

Other objects and advantages of the invention will become apparent from the following description 25 taken with reference to the drawing, wherein:

Figure 1 is a perspective view of the pipe racking chute positioned in a pipe racking bay in the derrick floor.

30 Figure 2 is a perspective view of another embodiment of the pipe racking chute having a motor and gear system for one of its actuating means.

Figure 3 is a diagrammatic view of another 35 embodiment of the pipe racking chute having a combination mechanical and hydraulic system for its actuating means.

Figure 4 is a perspective view of another 40 embodiment of the pipe racking chute utilizing power screws for its actuating means.

Figure 5 is a detail view of Figure 4.

Figure 6 is a bottom view along the line 6—6 in Figure 5.

Figure 7 is a diagrammatic view of another 45 embodiment of a pipe racking chute having an actuating means comprising winch and cable means.

Briefly, the pipe racking chute of the present 50 invention comprises a movable, trough-like sloping chute element mounted adjacent an opening in the floor of a well derrick for racking or positioning pipe stands racked through said floor opening, a pivot member hinged to one end of said chute, a pivot bearing mounted on the sub-structure of the derrick below the floor level

thereof so that the pivoted end of the chute is substantially at floor level, means for turning the pivot in its bearing whereby the attached chute is moved in a horizontal plane, and means cooperating with the other end of the chute for moving it in a vertical plane, whereby the end of a pipe stand placed in said chute is guided by said chute to any desired position within a suitable racking space which may preferably be formed by an opening in the derrick floor.

Referring to Figure 1 of the drawing, a typical derrick substructure 10 is shown in position over a well being drilled, having a rotary table 14 positioned in the operating floor 15 of said substructure. A trough-shaped pipe racking chute 16 is shown with its pivoted end 17 mounted in the substructure adjacent the rotary table, at substantially floor level, in a pipe racking well or space 18, while the other end 19 of the chute 16 extends into said racking space 18 in a downwardly sloping manner, being thus at a substantially lower level than the pivoted end 17 to facilitate the sliding of a pipe section 41 down said chute.

The cross-section of the chute 16 may be of any arcuate, semi-circular, or any other desirable concave shape suitable for receiving and guiding therein and therealong the lower end of a pipe member being disconnected from a string.

The pipe racking well or space 18 is arranged alongside the derrick, or is formed in a section of the operating floor 15 adjacent the rotary table 14, but preferably at the outer edge of said floor. As shown in Figure 1, the pipe racking well 18 is formed between two pairs of horizontal structural members 20 and 21, 22 and 23 of the substructure 10. Bearings 26 and 27, rotatably mounting a pivot pin or member 28 therein, may be fixedly attached by suitable means, as by welding, bolting, etc., to the structural members 22 and 24. Vertical movement of the pivot member 28 in a downward direction may be limited by a collar 29 secured to or integrally formed on said pivot 28, said collar 29 contacting said bearing 26. The upper end of the pivot member 28 has a vertical slot and a hole horizontally drilled at right angles to the slot. The slot receives a hinge member 30 having a hole drilled therethrough and fixedly attached to the lower side of one end of the chute 16. The hinge member 30 of the chute 16 and the pivot member 28 are secured in vertical hinged relation by a pin 31 which passes horizontally through the drilled holes of said members 28 and 30. Thus the racking chute 16 is mounted for movement in a vertical plane by hinge pin 31 and in a horizontal plane by pivot member 28, said hinge and pivot members forming in combination a universal joint.

Movement of the chute 16 may be accomplished by any suitable gear or lever means actuated by electrical, mechanical or hydraulic power means. One possible embodiment is shown in Figure 1 wherein hydraulic means are used to actuate the chute, said hydraulic means comprising first and second hydraulic cylinder 32 and 33 for moving the chute 16 in horizontal and vertical planes respectively. An arm 48 extending from one end of the first hydraulic cylinder 32 is affixed by means of a collar 34 to a vertical rod 35 attached to the substructure, whereby the cylinder 32 may be rotated in a horizontal plane. A rod 36 extending from the other end of the hydraulic cylinder 32 is fixedly attached to and actuated by a piston (not shown) within said cylinder 32. The other end of said rod 36 is pivotally connected to a lever arm or bar 37 rigidly attached to the pivot pin 28, which in turn is hinged to the chute 16 as previously described.

Hydraulic fluid is supplied to either side of the piston within the hydraulic cylinder 32 through hoses 38.

Similar hydraulic means are employed to move the chute 16 in a vertical plane. As shown in Figure 1, the second hydraulic cylinder 33 is mounted preferably at a lower level than cylinder 32 so as to supply the pressure and leverage necessary to support the chute 16 and to maintain it in position when the end of a heavy pipe stand 41 is resting on or sliding in said chute 16. At the same time, the second hydraulic cylinder 32 is located directly below or close to the pivot member 28 whereby the chute 16 and the cylinder 32 pivot about the same vertical axis or substantially adjacent axes. Thus, the second cylinder 33 or a rod 41 extending therefrom may be mounted by any suitable means, such as a hinge 42, etc., to an extending arm 43 whereby said cylinder 33 may be moved around said joint 42 in any vertical plane. Connected to the piston (not shown) within the cylinder 33 and extending from its other end is a piston rod 44 connected, as by a hinge 44, to the lower end 19 of the chute 16. Hydraulic control fluid is supplied to either side of the piston within the hydraulic cylinder 33 through hoses 45 and 46 extending from the control box 40, said box being situated at any desired location on or near the drilling rig.

When removing drill pipe from the borehole and racking sections of said pipe by the method of the present invention, elevators are removably connected to the top of the pipe string above the rotary table. A hoist drum and cable raise a traveling block, attached elevators and depending pipe string to a predetermined height. Slips are inserted in the rotary table around the drill string to anchor it temporarily so that one or more sections of pipe may be uncoupled from the drill string while the upper end of the pipe string is still supported by the elevators. This section of pipe depending from the elevators is then lowered to substantially floor level while its lower end is swung and lowered into the pivoted end of the pipe racking chute. Further lowering of the pipe section allows it to be guided by the chute and slid into its racking position at a level below the operating floor or rotary table, preferably the ground. Continued lowering of the pipe section sets the lower end thereof in its racked position while the upper end may be racked manually or by mechanical means to any desired position against the derrick, or a finger board or other racking means attached thereto. After the lower end of the pipe section has been set in position, and while the upper end is being moved to its racking position, the elevators may be disconnected from said upper end.

The positioning of the chute 16 is accomplished by the operation of the hydraulic cylinders through control box 40 before the pipe stand 41 enters the chute or at any time before it is set down on the ground or a pipe platform (not shown). After one stand of pipe 41 has been racked, the chute may be positioned for the next stand. The pivoted end 17 of the chute 16 is located preferably close to the rotary table so as to reduce the distance that the lower end of the pipe stand must be swung manually. Pipe han-

dling hazards are reduced by use of the chute of the present invention, and the danger of lowering a stand of pipe on a man's foot is eliminated as each stand is lowered into the chute. With one end of the chute being on a pivot, there is no indecision on the part of the operator as to where to place the end of the pipe stand, since every stand enters the chute at the same point. When using the present racking chute, the floor substructure need not have the usual heavy reinforced construction to support the pipe stands, as said stands are supported on the ground. With the pipe racked at a level below the operating floor of the rig, more space is made available for racking operations in the upper part of the derrick, and there is, for the same reason, more distance between the traveling block and the crown block when catching the stands of pipe during the "running in" operation, thus making it possible to catch stands at higher rates of speed without the hazard of running into the crown. When the elevators only partially engage, and momentarily lift a pipe stand, there is no hazard of the lower end of the falling pipe injuring anyone. Although the pipe racking chute is shown in connection with a permanent type derrick on a permanent type substructure, it may obviously be also employed when a portable derrick and/or substructure are used. The chute may also be used in combination with a truck-mounted rotary-table and derrick or mast whereby pipe stands are lowered to and racked on the ground, the term derrick being used herein to include all types of derricks and masts, either permanent or portable, that are used to remove pipe, casing, tubing or rods from a well.

As shown in Figure 2, another embodiment of the present invention may comprise a guide chute 16 hinged to a pivot member 28 having both electric and hydraulic prime mover means. Movement of the chute 16 in a vertical plane is attained by the hydraulic means comprising a hydraulic cylinder 133 secured by means of a hinge 41 to the lower end of the pivot member 28 for rotation therewith, a piston (not shown) mounted within said cylinder 133 and having a rod 43 connected thereto, which rod has its extending end pivoted or hinged on said chute 16, and hoses 45 and 46 for supplying fluid pressure to said hydraulic cylinder 133. Mounted on the pivot member 28 is a worm wheel 48 which meshes with a worm 49 attached to the shaft of a reversible hydraulic or electric motor 50 which, when started, rotates the pivot member 28 and attached chute 16 in a horizontal plane.

Another embodiment of the present invention, as shown in Figure 3, may comprise the guide chute 16 secured by means of a hinge member 52 to a pivot member 53, said chute having both mechanical and hydraulic prime mover means. The hydraulic means may be in the form of a hydraulic cylinder 54, secured to pivot member 53, said cylinder having a piston member (not shown) slidably mounted therein and fluid pressure conduit 56 leading thereto for actuating said piston. The pivot member 53 is rotatably mounted in any suitable manner, as in bearings 57 and 58 which may be fixedly secured to structural members 59. Movement of the chute 16 in a horizontal plane is attained by a crank 60, gear 61 and gear 62 secured to the pivot member 53. The crank 60 may be hand or power operated. A member 63 is slidably mounted in tubular lower part of the pivot 76

member 53, said member 63 being secured to an extending arm 64 of the hydraulic piston member by a pin 97. The slideable member 63 has a hinge 66 secured thereto which extends through a longitudinal slot 68 in the tubular wall of said pivot member 53 and is slideable within said slot. A lever arm 65 is attached at one end to the hinge 66 on the member 63, and at the other end to a slideable hinge 67 on the lower end of the chute 16 comprising a slideable pin 51 in a slot 55. Thus, it will be seen that movement of the chute in a vertical plane, as from the position shown at A to a position shown by broken lines at B, results when the hydraulic piston member is actuated. In order to secure a proper mechanical advantage while the chute is substantially in a vertical position, two spaced plates 201 are attached to the chute so that their edges 202 slide on the pin 66. The slope of the edges 202 is such that any vertical movement of pin 66 causes a corresponding movement of the chute 16 in a vertical plane. During this operation the lever arm 65 is not effective and the hinge pin 51 slides in the slots 55 of the hinge 67 at the lower end of the chute 16.

The present chute positioning or actuating means may likewise have the form shown diagrammatically in Figure 4. Power screws 84 and 85 are rotatably mounted in bearings 87 and 88 on structural members 70 and 71 adjacent the pipe racking well in the derrick substructure. A reversible motor 86 rotates the power screw 84 in bearing 87 and, through gear boxes 89 and 90 and shaft 91, rotates also the other power screw 85. Movable bearing blocks 79 and 80 are mounted on the power screws 84 and 85. Carried between these blocks is a power screw 78. The shaft 83 of a reversible motor 81 is connected to and drives power screw 78, which in turn actuates a movable block 77 mounted thereon. The block 77 has an internally-threaded horizontal bore therethrough and is designed for movement along the power screw 79. The upper end of a pipe racking chute 73 may be affixed to a universal joint, as previously described, said universal joint comprising hinge means 74, pivot means 75, and bearing means 76 secured to a structural member 72. The middle or lower end of the chute may be slidably and rotatably mounted on movable block 77 in any suitable manner. For example, as shown in Figures 5 and 6, two spaced parallel bars 92 and 93 may be affixed to the lower side of the chute 73 in spaced relationship thereto. Slidably mounted between said bars 92 and 93 and the chute is a cross bar 94 which is rigidly secured to block 77 by a rod 95, thus permitting movement of the chute 73 with relation to the block 77 while remaining affixed to said block 77 and supported thereby. Thus, in the above-described apparatus, movement of the block 77 along the power screw 78 will result in a movement of the chute 73 in a horizontal plane while movement of the block 77 in a direction parallel to the power screws 84 and 85 will result in a movement of chute 73 in a vertical plane.

Still another embodiment of the present invention, as shown in Figure 7, may comprise a guide chute 101 secured by means of a hinge member 102 to a tubular pivot member 103, which is rotatably mounted in bearings 104 and 105 that are suitably affixed to the substructure 106. Any suitable electrical, mechanical or hydraulic prime mover means may be employed to rotate the pivot member 103 and its attached

chute 101 in a horizontal plane, as for example by a motor 120 through gears 121 and 122. Movement of the chute 101 in a vertical plane is obtained by means of a lever arm comprising links 107 and 108 hinged together at 109. The other end of link 107 is hinged to the lower end of the chute 101 at 110 while the other end of link 108 is hinged at 111 to a member 112 that is rigidly secured to, and rotatable with, the pivot member 103 as shown. All the above-mentioned hinged connections are adapted for movement in a vertical plane only.

Movement of the lever arm links 107 and 108 and the attached chute 101 in a vertical plane is effected by means of a wire line or cable 113 attached to hinge 109 which passes between sheaves 114 and 115 up through and out the tubular pivot member 103. The wire line 113 passes over a sheave 116 to a winch reel 117 secured to a motor 118 which may be bracketed to said pivot member 103. In operation the chute 101 is displaced outward as the wire line 113 is wound on the winch reel.

While any of the above-described embodiments of the chute may be used in a substructure of any derrick, it has been found that the embodiment of the chute shown in Figure 1 is preferred where there is sufficient room in the substructure to install the prime mover means and where the movement of the chute in a vertical plane is relatively small. The embodiment shown in Figure 3 is preferred where the clearances in the substructure are critical and the throw of the chute in a vertical plane is nominal while the embodiments of Figures 4 and 7 may be used when the movement of the chute in a vertical plane is relatively great.

I claim as my invention:

1. For use at a derrick installation, a pipe racking device comprising a downwardly sloping trough-like chute element adapted to receive and to guide therealong the lower end of a pipe, a supporting pivot member vertically mounted on the derrick, gear means mounted on said pivot member for rotating said pivot member about a vertical axis, horizontal pivot means

5 connecting the supporting pivot member to the chute element near the upper end thereof, a hinged lever arm secured to the chute element near the lower end thereof, cable means fastened to said lever arm, and winch means for winding and unwinding said cable means, thereby raising and lowering said lever arm to rotate said chute element about said horizontal pivot means.

10 2. A derrick installation comprising an elevated derrick floor having a bay therein, suspension means for moving tubular members vertically above said floor, and a chute structure positioned within the bay for racking said tubular members and lowering them within the bay, a sloping elongated guide having an unobstructed trough-like upper surface to permit the lower ends of said suspended tubular members to slide therealong, a pivotal connection consisting of vertical and horizontal hinged elements rotatably supporting said guide on the derrick installation, the upper end of said guide being substantially at the level of the derrick floor, and prime mover means connected between the underside of said guide and the derrick installation for rotatably actuating said chute about said pivotal connection in a vertical and a horizontal plane, whereby the tubular members lowered by said suspension means are directed through the derrick floor bay by the engagement of their lower ends with said guide element to a vertical racking position with said lower ends supported at a level below that of the derrick floor.
